SURFACE ORNAMENTATION

Byron E. White, Kalamazoo, Mich., assignor to
Globe Casket Manufacturing Company, Kala-
mazoo, Mich.

Application November 5, 1934, Serial No. 751,520

3 Claims. (Cl. 41—34)

The main objects of this invention are:

First, to provide an improved covering which is especially well adapted for ornamenting the surfaces of funeral furniture such as caskets, catafalques, pedestals, pulpits and the like, which is beautiful in appearance, and tough and very durable and serviceable, and economical to manufacture.

Second, to provide an improved method of 10 ornamenting the exposed surfaces of funeral furniture and the like, which is economical and which permits the production of a final ornamentation of any desired effect or color.

Third, to provide a structural unit which is 15 simple and economical in its parts and which is durable and has a characteristic surface appearance.

Objects relating to details and economies of my 20 invention will appear from the description to follow. The invention is defined and pointed out in the claims.

A structure which is a preferred embodiment of my invention is illustrated in the accompanying drawing, in which:

Fig. 1 is a view in side elevation of a casket embodying the features of my invention.

Fig. 2 is an enlarged fragmentary perspective view of a sheet of kraft crepe paper, one of the elements.

Fig. 3 is an enlarged fragmentary transverse section taken on a line corresponding to line 3—3 of Figs. 1 and 4.

Fig. 4 is an enlarged fragmentary plan view of my surface ornamentation.

Fig. 5 is a view similar to Fig. 4, after the application of the desired color to the material.

Referring to the drawing, 1 is a casket and 2 is a sheet of heavily creped kraft paper or parchmentized paper which I prefer to use. The outer surface of the body 3 of the casket and the inner surface of the paper are first covered with glue or cement 5. The paper is then applied to the casket and the glue is permitted to harden and cement the paper to the body. The corrugations 6 of the paper are preferably arranged to extend vertically of the casket 1 to give the latter the appearance of being covered with pulled fabric, such as silk.

The casket is thus made ready for stock or supply storage, so that when a casket is ordered in a certain desired color, it may be removed from storage and lacquer of the proper color or other suitable coloring matter may be applied to the paper. In the drawing, the colored lacquer is indicated at 7, Fig. 3. When the material is

coated with silver lacquer, it has the appearance of drawn or pulled metallic-like white silk, a very beautiful surface ornamentation especially for funeral furniture. A final treatment with colorless lacquer 8 is made to increase the brilliance of the surface of the paper and give it a high gloss, making a very beautiful covering.

By not coating the material with colored lacquer for stock or storage, I provide a great saving inasmuch as it is necessary for the dealer or manufacturer to carry in stock only a relatively few of the caskets, the final color being supplied on order. In the past, it has been necessary to carry a stock of caskets in different colors, which is a great overhead and storage expense to both the manufacturer and the dealer, or it has been necessary to carry them in the rough and apply the fabric covering to specification. As the application of the fabric covering is expensive and is quite a slow process, the advantages of the present method are apparent. This is a highly important feature of my invention.

While I have shown the entire exposed outer surface of a casket covered in accordance with my invention, it is to be understood that my improved covering can be used in combination with cloth and the like, and further, the invention is applicable to caskets of various shapes and sizes and to other articles of furniture and especially such articles of furniture which are used for funerals. The furniture or other article ornamented in accordance with my invention is not only simple and economical to manufacture, but it resists temperature changes inasmuch as breaking of the paper due to the contraction and expansion of the wood is obviated.

The gluing of the creped paper to the foundation or body 1 and the application of the lacquer coating makes the raised portions of the paper stiff and rigid and maintains the shape thereof permanently.

Another feature is the beautiful appearance of the furniture covered in accordance with my invention. The heavily creped kraft paper has a very characteristic appearance especially when colored and given a reflecting surface. It has a soft and rich effect which blends in well with funeral furniture. Further, the covering is waterproof and durable to a marked degree. In caskets, it is highly desirable that the surface ornamentation resist moisture as much as possible. In wood caskets, this not only preserves the ornamentation, but also the body of the structure.

Where silver and gold colors are used, the casket 55

has the appearance of being made of metal, which is a desirable feature in so far as the appearance of the casket is concerned. Thus, the casket is made to look very rich and expensive, although in fact its cost is very low compared to that of one actually formed of metal. However, I do not wish it to be understood that my invention is limited to a backing of wood for the surface ornamentation, because the backing for the ornamentation may be any suitably stiff and substantially rigid material.

I have illustrated and described my improvements in an embodiment which I have found very practical. I have not attempted to illustrate or describe other embodiments or adaptations, as it is believed this disclosure will enable those skilled in the art to embody or adapt my improvements as may be desired.

Although I have shown and described a certain specific embodiment of my invention, I am fully aware that many modifications thereof are pos-

sible. My invention, therefore, is not to be restricted except in so far as is necessitated by the prior art and by the spirit of the appended claims.

Having thus described my invention, what I claim as new and desire to secure by Letters Patent is:

1. The combination with a backing panel, of a sheet of parchmentized kraft crepe paper glued to said panel, a coating of colored lacquer on said sheet, and a coating of transparent lacquer on said colored lacquer coating.

2. The combination with a backing panel, of a sheet of parchmentized kraft crepe paper glued to said panel, and a coating of lacquer on said sheet.

3. The combination with a non-flexible backing, of a covering therefor of parchmentized kraft paper glued to said backing, and a protective coating of lacquer on said covering.

BYRON E. WHITE.
